US0D1011181S

(12) **United States Design Patent** (10) **Patent No.:** **US D1,011,181 S**
(45) **Date of Patent:** **** Jan. 16, 2024**

(54) **NUT AND TOOL SET**

(71) Applicant: **Saris Equipment, LLC**, Edison, NJ (US)

(72) Inventor: **Chad DeBaker**, Minneapolis, MN (US)

(73) Assignee: **SARIS EQUIPMENT, LLC**, Edison, NJ (US)

(**) Term: **15 Years**

(21) Appl. No.: **29/757,748**

(22) Filed: **Nov. 9, 2020**

(51) LOC (14) Cl. **08-08**
(52) U.S. Cl. **USPC D8/397; D8/387**

(58) **Field of Classification Search**

(57) **CLAIM**

The ornamental design for a nut and tool set, as shown and described.

DESCRIPTION

FIG. 1 is a top perspective view of a nut and tool set, showing my new design;

FIG. 2 is a bottom perspective view thereof;

FIG. 3 is a front elevational view thereof;

FIG. 4 is a rear elevational view thereof;

FIG. 5 is a right-side elevational view thereof;

FIG. 6 is a left-side elevational view thereof;

FIG. 7 is a top plan view thereof; and,

FIG. 8 is a bottom plan view thereof.

The broken lines in the figures depict portions of the nut and tool set that form no part of the claimed design.

1 Claim, 5 Drawing Sheets
